(57) **CLAIM**

The ornamental design for a wing bracket, as shown and described.

DESCRIPTION

FIG. 1 is a perspective view from the top-left of the wing bracket;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view from the bottom-right thereof. The features shown in broken lines are for the purpose of illustrating portions of the article that form no part of the claimed design.

1 Claim, 6 Drawing Sheets

FIG. 1

FIG. 2

FIG. 3

FIG. 4

FIG. 5

FIG. 6

FIG. 7

FIG. 8
